Specification for Design.

Patented Feb. 20, 1917.

Application filed December 15, 1916. Serial No. 137,271. Term of patent 14 years.

To all whom it may concern:

Be it known that I, EDGAR MOTT BOTTOME, a citizen of the United States, and residing at Moundsville, in the county of Marshall and State of West Virginia, have invented a certain new, original, and ornamental Design for a Glass Article, of which the following is a specification, reference being had to the accompanying drawings, forming a part thereof, wherein—

Figure 1 is a side elevation of a drinking glass of conventional form embellished with the new design and illustrating a portion

of the latter, and Fig. 2 is a similar view of the glass illustrating the remainder of the design. The design, which consists of the configuration shown, may be formed in or on the surface of drinking glasses, dishes, vases and other glass articles.

I claim:—

The ornamental design for a glass article, substantially as shown and described.

EDGAR MOTT BOTTOME.
